DESIGN FOR A BAG OR THE LIKE

Elie Meltzer, Plainfield, N. J.

Application March 21, 1942, Serial No. 106,274

Term of patent 14 years

To all whom it may concern:

Be it known that I, Elie Meltzer, a citizen of Russia, and a resident of Plainfield, in the county of Union and State of New Jersey, have invented the new, original and ornamental Design for a Bag or the like, of which the following is a specification, reference being had to the accompanying drawing, forming part thereof, in which

Fig. 1 is a side elevational view of a bag or the like showing my design with the bag illustrated in open position;

Fig. 2 is an end elevational view of the bag;
Fig. 3 is a top plan view of the bag; and
Fig. 4 is a side elevational view of the bag showing it in closed position.

I claim:

The ornamental design for a bag or the like, substantially as shown.

ELIE MELTZER.
